UNITED STATES PATENT OFFICE.

HARRY COHEN, OF NEW YORK, N. Y.

UNDERGARMENT.

Application filed February 14, 1925. Serial No. 9,093.

This invention relates to undergarments for women, and has to do more particularly with an undergarment of the type commonly known as a slip, although as the details of 5 the invention are made clear, it will be apparent that it may be embodied in undergarments of various other types, of which the slip is merely an example.

At the present time, summer and evening 10 dresses are made of such light, sheer fabrics, that it is necessary to wear a shadow-proof garment beneath them. This garment is generally a slip, which consists of a skirt and bodice in one piece, supported by shoulder straps. Ordinarily this slip is of the 15 same color and shade as the dress itself, and it may consist of front and rear panels united along their edges to form seams at the sides of the garment. The latter is 20 usually of considerable fullness, and is gathered appropriately at the waist. It has a deep hem at the lower edge, to provide a double thickness of material at this point, and is of a length such that it terminates 25 shortly above the lower edge of the dress. When this combination of dress and slip is worn, additional undergarments, either one or two-piece, are also worn, and although the dress and the undergarments may be 30 made of light materials, still the combination is frequently uncomfortable in hot weather, and also when the wearer is dancing. With the slip made in the manner described; that is, resembling a skirt at its lower end, 35 modesty requires that the additional undergarments be worn with it.

The object of this invention is to provide an undergarment of the slip type, so constructed that it may be worn modestly without 40 additional undergarments. For this purpose the improved slip is constructed in the form of a skirt and bodice of shadow-proof material, provided with a deep hem at its lower edge in the usual manner, but 45 extending between the front and rear portions of the hem there is attached a partition member which divides the lower end of the skirt so as to form drawer legs. This partition is formed of two pieces, cut in the 50 manner presently to be described, which is at one end attached directly to the hem, while at the other, the ends of the two pieces which form the partition are separated and used as a part of this hem. The partition is preferably 55 arranged in such a way that it lies adjacent the upper edge of the hem and is

so formed that it has a considerable degree of elasticity, which is provided not only by the manner in which the partition itself is formed, but also by the way in which 60 it is secured in place; also the manner in which this member is made and secured in position permits the two pieces of which it is formed to be cut from the cloth in a most economical manner.

Slips as commonly placed on the market are of varying sizes as to bust measurement, and of standard lengths which depend on such measurements. As this length may not be the one which the wearer requires, it is 65 customary to make the slips somewhat longer than will probably be required, and form the hem in such a way that it can be raised within the garment so that the lower edge of the garment may be turned 70 in. With the slip formed according to the present invention, since the partition member is attached only to the hem, and to some extent forms part of that hem, the raising or lowering of the hem, as may be required, 75 will also raise or lower the partition to the desired extent.

While the method of forming the partition will be described in its adaptation for use with a slip, it will be apparent that it 80 may be used with various other garments. In the accompanying drawings, however, the garment illustrated is of the slip type, and in these drawings,

Fig. 1 is a view in perspective of the improved slip,

Fig. 2 is a sectional view on the line 2—2 of Fig. 1,

Fig. 3 is a cross-sectional view on the line 3—3 of Fig. 2,

Fig. 4 is a cross-sectional view on the line 4—4 of Fig. 2, and

Fig. 5 is a plan view of the two members which make up the partition.

The garment illustrated in Fig. 1 is a 100 standard form of slip, consisting of a front panel 10, and a rear panel 11, which are united by seams which extend lengthwise of the garment. The front panel is customarily made of considerably greater width than the rear panel, and is gathered on either side, as at 12. Below the gathers the slip terminates in a skirt portion 13, of considerable fullness, and at the top it is provided with shoulder straps 14, which are sewed 105 to an inturned hem 15.

This garment is ordinarily made of a

somewhat closely woven material, such as radium silk, and at the lower edge it is provided with a hem 16, of considerable depth, so that the skirt portion is formed of a double thickness of the material. This type of garment is usually sold with the hem loosely basted or tacked at its upper edge 17 so that the length of the slip may be altered simply by raising the hem, or lowering it, and securing its upper edge in place at the desired height.

The hem consists of three pieces of material which are more clearly shown in Fig. 2. The main body of the hem is formed of a strip of material 18 which extends from a point at one side of the middle of the back, around the front of the garment, to a point spaced a similar distance from the middle of the back on the opposite side. The other two portions of the hem are made of pieces 19, shown in Fig. 5, which consist of straight portions 20 and extending tabs 21. These tabs are cut with inwardly curving upper and lower edges 22 and the end 23 of each tab is of greater width than the distance across the central portion of the latter. These two pieces are stitched along their edges 24 to the ends of the straight piece 18, the stitching being shown at 25 in Fig. 2. The upper and lower edges 26 and 27 are then secured to the rear panel of the slip and then the tabs are folded so as to lie face to face, in the manner illustrated in Fig. 2. These tabs are then stitched along their curving edges 22, so as to form a partition member which is united to the front panel of the slip by stitching to the hem at 28. It will be observed that the members 19 are united at their ends to the member 18 of the hem, and the tabs lie between the upper and lower edges, which are united to the rear panel. This gives the tab members a considerable degree of elasticity, which is also increased by reason of the fact that along the curving lines 22 the material is cut on the bias.

With this arrangement it will be observed that the partition divides the skirt at the lower end into drawer legs, the partition preventing the slip from working upwardly. The novel manner in which the partition is made not only improves the strength of the partition, but, because the latter is united to the hem, it does not have a tendency to pull the front and rear panels together, since the hem is quite wide at its mid-point and is free to separate to a considerable degree from these panels. The partition formed in the manner described, is disposed at a height which cannot cause discomfort, and since the partition is secured only to the hem and forms an integral

part of the latter, when the garment as purchased, is found to be too long, the turning of the hem also raises the partition to the desired extent. The method of forming the partition not only provides a great degree of elasticity and makes the partition strong, but it also permits the material to be used most economically. Ordinarily the cloth of which such garments are cut, comes in 40" width. The pieces 19 and 20 of which the partition is made are 20" from the edge 23 to the edge 24, so that two of these pieces may be cut in a single width across the length 75 of cloth, and in this operation there is very little waste. The circumference of the slip at the lower edge is approximately 60", so that the large piece which goes to make up the hem is cut from a piece which extends 80 entirely across the goods. The length of the tabs is preferably 10", so that the body portion of the smaller members is also 10". Thus the portions of these smaller pieces which are united to the hem, plus the length 85 of the large piece, equals the 60" required at the circumference.

While the garment with the partition has been described as being of the slip type, it will be evident that the features of the invention are by no means limited to that particular kind of garment, since it may be used with any garment similar to a skirt to equal advantage. The slip shown in the drawings is a so-called "step-in", but this 95 novel partition may be used equally satisfactory in a garment which consists only of a skirt portion and does not include the bodice.

I claim:

1. In an undergarment, a skirt portion having a hem disposed at the lower edge and on the inner side thereof and adapted to be raised or lowered to shorten or lengthen the skirt, and a vertical partition attached to said hem and extending across the skirt from front to rear and forming drawer legs.

2. In an undergarment, a skirt portion having a hem disposed at the lower edge 110 and on the inner side thereof and adapted to be raised or lowered to shorten or lengthen the skirt, the hem being formed of a member which extends through the greater part of the circumference of the skirt, and two vertically positioned smaller members united to the ends of the first member and completing the hem, the smaller members terminating in tabs which are united at their ends to the larger member and providing a vertical partition across the skirt portion from front to rear to form drawer legs.

In testimony whereof I affix my signature.
HARRY COHEN.
